MUSICAL INSTRUMENT TUNING APPARATUS

Lester B. Holmes, Garden City, Kans.

Application August 10, 1936, Serial No. 95,212

12 Claims. (Cl. 84—454)

This invention relates to apparatus for tuning musical instruments or for observing and analyzing sound waves. More particularly, this invention relates to visual observation apparatus adapted to generate certain predetermined standard frequencies having certain predetermined intervals therebetween for tuning musical instruments or determining when certain sound frequencies are of a predetermined pitch or pitches.

- 10 An object of this invention is to provide an oscillation generator having means for generating a series of predetermined frequencies and a cathode ray device adapted to have one of said predetermined standard frequencies impressed thereon simultaneously as a sound modulated electric current is impressed thereon whereby the frequency characteristics of the standard frequency and the sound may be observed on the screen of the cathode ray device.
- 15 Another object of this invention is to provide a device for determining sound frequencies, said device having an oscillation generator adapted to generate any one of a selected number of frequencies and an electrically energized visual observation device adapted to receive electrical oscillations from said oscillation generator corresponding to said selected frequency and electrical sound modulated oscillations corresponding to the frequency of the sound being measured whereby frequency differences that may exist between the oscillation generator frequency and the sound frequency may be rendered visible.

A further object of this invention is to provide a standard frequency device and an indicating device having means for impressing a selected standard frequency on the circuits thereof together with a sound modulated electric current for producing a visual indication of any frequency differences that may exist between the standard frequency and the sound frequency.

Other and further objects of this invention will be apparent to those skilled in the art to which it relates from the following specification and the claims.

- 45 In accordance with this invention I provide a visual indicating apparatus employing a device, such as a cathode ray tube, having means for generating a cathode ray and deflecting electrodes for moving the cathode ray beam over a screen in accordance with electrical potentials of a predetermined frequency and a sound frequency impressed on said electrodes. A standard frequency oscillator employing a series of twelve tuning forks, for example, having frequencies spaced at predetermined intervals, such as are employed in

an octave of a piano scale, for instance, from each other, is connected to electrodes of the visual cathode ray device together with the output of the sound pick-up amplifier in such a manner that the cathode ray is caused to produce predetermined figures on the screen of the cathode ray device when the sound frequency bears a certain relationship or relationships to the standard frequency being produced by the standard frequency oscillator.

10 By selecting any one of the predetermined number of tuning forks and causing the standard frequency oscillator to produce oscillations of a frequency corresponding to the tuning fork, the frequencies of different sounds, produced by a 15 musical instrument, for example, may be measured, matched, or observed on the screen of the cathode ray device.

The apparatus of this invention is very simple in use and enables a person to tune a musical 20 instrument to a predetermined standard frequency by sight. The apparatus also may be employed in the instruction of music and in demonstrating principles of sound physics.

Further details of this invention will be ap- 25 parent from the following specification and the drawings in which, briefly,

Figure 1 shows a schematic diagram of the circuit arrangement employed;

Figures 2 and 3 are detailed views showing the 30 mounting of the tuning forks and associated apparatus;

Figures 4, 5, 6, and 7 show different frequency patterns that may be obtained on the cathode ray tube screen, and Figure 8 shows the control 35 panel of an apparatus constructed in accordance with this invention.

Referring to Figure 1 of the drawings in detail, reference numeral 1 designates a cathode ray tube having deflecting plates 2 and 3, anodes 4 40 and 5, grid electrode 6, cathode 7, and heater electrode 8.

A source of direct current supply is connected to the terminals 12 and 13. This source may be a generator, battery, or a rectified and filtered 45 alternating current supply, such as the supply 14. A condenser 15 is connected across the terminals 12 and 13 together with a voltmeter 16 and a series of resistance units 9, 10, and 11. These resistance units are employed as voltage 50 dividers for the purpose of impressing predetermined or variable voltages on selected electrodes of the tube 1 as is hereinafter described. The connection 17 between the resistors 9 and 10 is employed to connect the cathode 7 to the direct 55

current source of supply. A variable contact and connection 18 provided to the resistor 9 is used to impress a negative voltage on the grid electrode 6 of the tube 1 with respect to the cathode 7. A similar variable connection 19 is provided to the resistor 10 for impressing a positive potential on the anode 5 with respect to the cathode 7. One of each of the sets of deflector plates 2 and 3 is connected to the anode 4 which 10 is connected to the positive terminal 13 and to the resistor 11.

The microphone 20 is connected across the resistor 21 to the grid electrode of the amplifier tube 22 and the grid bias resistor 23. A bypass 15 condenser 24 is connected across the resistor 23 which is connected into the cathode circuit of the tube 22. The anode of the tube 22 is connected to the primary of the coupling transformer 25, the secondary of which is connected 20 to the control grid of the amplifier tube 26. A grid bias resistor 27 and bypass condenser 28, similar to those of the tube 22 are connected into the cathode circuit of the tube 26. The anode of the tube 26 is connected to the primary of 25 the transformer 27 and the secondary of this transformer is connected across the resistor 28 associated with the cathode ray tube 1. The resistor 28 is connected in series with the resistor 29 between one deflector plate of each set of deflector plates 2 and 3. The connection between the resistors 28 and 29 is also joined to the anode 4 of the tube 1.

The tuning fork oscillator 30 comprises an oscillator tube 31 having cathode, anode, and grid electrodes, a pair of transformers 32 and 33, a tuning fork 34 and tuning fork transformers 35 and 36. The transformer 32 is connected between the grid and cathode electrodes of the tube 31 and the tuning transformer 35. The 40 transformer 33 is connected between the cathode and anode electrodes of the tube 31 and the tuning fork transformer 36. The secondary of the transformer 33 is also connected to the primary of the transformer 37 and the secondary of this 45 latter transformer is connected across the potentiometer 38.

Two electric discharge devices 39 and 40 are employed in accordance with this invention to produce electrical oscillations of a sawtooth wave 50 form. The electric discharge device 39 is of the pentode type and is employed as a substantially constant current conducting device for periodically charging the condenser 41 after this condenser is periodically discharged through the 55 gaseous three-electrode discharge device 40. The grid electrode of the discharge device 40 is connected to the variable contact 42 of the potentiometer 38 and the operation of this discharge device is accordingly controlled by the tuning fork 60 oscillator 30 to discharge this condenser at a frequency determined by the frequency of the tuning fork oscillator. A resistor 43 is connected in series with the grid of the discharge device 40 as a current limiting device. A terminal of the 65 secondary of the transformer 37 is connected to one of the grid electrodes of the pentode 39 and to the voltage divider 44 which is connected across the output terminals of the current supply 14. The cathode and the auxiliary grid electrode of 70 the discharge device 39 are connected through the resistor 45 to the control grid of this discharge device and to the negative terminal of the current supply source 14. This resistor 45 is employed to maintain the cathode and the 75 control grid of the discharge device 39 at proper

biasing potentials with respect to each other. The anode of the discharge device 40 is connected to the positive terminal of the current supply source 14 through the resistor 46 which is also employed as a current limiting device. The condenser 41 is connected to the cathode of the discharge device 40 and to the anode of this discharge device through the resistor 46. This condenser may be made variable so that the time interval of its charge through the constant current 10 tube 39 may be controlled by varying its capacity. Another way of varying this time interval is by increasing or decreasing the current flow through the tube 39. A coupling condenser 15 47 is provided between the cathode of the discharge device 40 and the resistor 29 which is connected to one of the deflector plates 2 of the cathode ray tube 1. The resistor 48 is connected across the output of the sawtooth oscillation generator, one terminal of this resistor being 20 connected to the condenser 41 and the other terminal being connected to the condenser 47. This resistor may be made of a value such as to discharge the condenser 41 periodically to operate the saw tooth oscillator at some determinable 25 frequency so that the tuning fork oscillator will have to function only as a master oscillator for controlling the saw tooth oscillator frequency. The output of the saw tooth oscillation generator is connected across the resistor 29 and across 30 the deflector plates 2 of the cathode ray tube to swing the beam of the cathode ray tube horizontally at a frequency corresponding to the frequency generated by the tuning fork oscillator. The wave form of this saw tooth oscillator resembles the teeth of a saw in that it rises gradually in value up to a maximum and then practically instantly drops to minimum.

The source of current supply 14 includes a transformer 49 which is provided with a primary 40 50 adapted to be connected to a 110-volt alternating current lighting circuit, if desired. Filament heating secondary windings 51, 52, and 53 for heating the filaments of the discharge devices 39, 54, and 40, respectively, are also provided to the transformer 49. A relatively high voltage secondary 55 connected to the anode electrodes of the rectifier discharge device 54 and to the filter condensers 56, is also wound on the core of the transformer 49. The output of this 55 secondary winding 55 is rectified by the rectifier discharge device 54 and filtered by the filter circuit comprising the condensers 56 and the resistance or choke coils 57. The output of this filter circuit is connected to the positive and 60 negative terminals of the power supply.

The anode circuits of the amplifier tubes 22 and 26 also may be energized from the power supply source 14 or if desired, separate sources of current supply may be employed for these amplifier tubes. A separate source of current supply 31a has been shown for the tuning fork oscillator tube 31. However, it is apparent that this oscillator tube also may be energized from the power supply source 14. The positive terminal of 65 the power supply source 14 is connected to the metal chassis or cabinet of the cathode ray tube, the cathodes of the amplifier tubes, and the tuning fork oscillator tube cannot be connected to the cabinets but must be electrically isolated 70 therefrom if the same source of anode current supply is to be used for the tuning fork oscillator and the amplifier tube as is used for the cathode ray tube. It is desirable to shield the different units, such as, the tuning fork oscil- 75

lator, the amplifier and cathode ray tube circuits from each other to prevent undesired electrical coupling.

In Figure 2 I have shown the preferred method of mounting the 12 tuning forks, employed in the tuning fork oscillator, upon a rotatable carrier 60. Figure 3 illustrates the manner in which the tuning fork 34 is supported between the windings of the transformers 35 and 36. Suitable brackets 35a and 36a which clamp the windings 35 and 36, respectively, and support these windings on a panel 35b are provided to the transformers 35 and 36, respectively. These brackets function to support the transformers 35 and 36 rigidly with respect to the forks of the tuning fork positioned therebetween. The end of each of the tuning forks is provided with a suitable nut, such as, the nut 34b, to fasten the respective forks to the rotatable carrier member 60 which is preferably of relatively massive construction in order to reduce vibration thereof when the tuning forks supported thereby are set into vibration. I employ a hammer having a head 62 made of relatively soft rubber, felt, leather, or similar material supported by the elongated spring-like member 63 in such a manner that the head 62 will strike succeeding ones of the tuning forks as the carrier member 60 is rotated by the shaft 64 in the direction designated by the arrow. The carrier member 60 is fastened to the shaft 64 by the set screw 65. The shaft 64 extends through a suitable hole in the panel 66 and has attached to the end thereof a suitable knob 67, shown in Fig. 8, which is employed for rotating the carrier member 60. The front of this panel 66 is provided with a series of twelve legends extending around a circle, the center of which coincides with the center of the knob 67. These legends correspond to the chromatic scale of a piano and are designated as c, c#, d, d#, e, e#, f, f#, g, g#, a, a#, b. These are the tones produced by the tuning forks supported by the rotatable carrier member 60 as designated in Figure 2.

As the knob 67 is rotated, different ones of the tuning forks supported by the carrier 67, corresponding to the different tones of the chromatic scale, are brought into position between the tuning fork transformer windings 35 and 36. Simultaneously, the pointer 68 of the knob 67 indicates on the front of the panel 66 which tuning fork is in position between the tuning fork transformer windings. As the different tuning forks are brought into position between the transformer windings, they are given a light tap by the head 62 of the hammer. Thus the tuning fork brought into position is set into vibration and through a feed-back action between the output and input circuits of the electric discharge device 31 the tuning fork is maintained in vibration as long as the electric discharge device 31 is energized.

The operation of this apparatus is as follows. In tuning a given note, for example, that corresponding to A of a piano to a standard pitch of 440 cycles per second, to determine if the string corresponding to this note is in tune, the operator rotates the knob 67 until the pointer 68 is opposite the position marked A. This rotates the tuning fork corresponding to A into position between the tuning fork transformers 35 and 36. The tuning fork is set into vibration when it is moved into this position inasmuch as it is tapped lightly by the hammer 62 and the tuning fork oscillator is caused to generate electrical oscillations corresponding to 440 cycles per second. The output

of the tuning fork oscillator is fed to the saw tooth oscillator which produces a pulsating current corresponding to the frequency of the tuning fork oscillator but having a different wave form suitable for controlling the sweep circuit of the cathode ray tube. The deflector electrodes 2 of the cathode ray tube are included in the sweep circuit of this tube and control the horizontal movement of the cathode ray beam, that is, the electrical potential impressed upon these electrodes causes the cathode ray beam to sweep horizontally across the screen of the tube. For this reason electrical potentials having saw tooth wave form must be applied to these deflector electrodes inasmuch as the cathode ray beam must be swept across the tube screen in a predetermined time interval and then practically instantaneously returned to its original or starting position to repeat the sweeping cycle. This will be more clearly explained in connection with the explanation of Figures 4, 5, 6, and 7.

The sound from the musical instrument being tuned is picked up by the microphone 20 and translated into corresponding electrical vibrations which are amplified by the amplifier tubes 25 22 and 26 and associated circuits. The output of the amplifier is impressed on the deflector electrodes 3 of the cathode ray tube. These deflector electrodes are positioned substantially at right angles to the deflector electrodes 2 as is customary in cathode ray tube design, and control the movement of the cathode ray beam in the vertical direction. Thus when the frequency of the sound picked up by the microphone 20 is the same as the frequency of the tuning fork oscillator, the figure observed on the cathode ray tube screen will be substantially like that illustrated in Figure 4. The instantaneous values of the sound wave intercepted by the microphone 20 over a complete cycle of the sound wave are exhibited on the screen of the cathode ray tube and a pattern similar to that shown in Figure 4 is obtained inasmuch as the time interval of one cycle of the sound wave intercepted by the microphone 20 corresponds to one cycle of the tuning fork oscillator. When this is the case, the figure exhibited on the cathode ray tube screen appears to be stationary. When the string of the musical instrument under observation is one-half the frequency of the tuning fork oscillator frequency, the pattern exhibited on the cathode ray tube screen is substantially like that illustrated in Figure 5. The pattern illustrated in Figure 4 will be present dimly in the background in the pattern illustrated in Figure 5, inasmuch as this pattern corresponds to the second harmonic. When the frequency of the string under observation is twice the frequency of the tuning fork oscillator, the pattern exhibited on the cathode ray tube screen will be that corresponding to Figure 6. Likewise, when the frequency of the string under observation is three times that of the standard frequency, the pattern will correspond to that shown in Figure 7.

I have illustrated the deflector plates 2 and 3 65 of the cathode ray tube in Figures 4, 5, 6, and 7 on the outside of the tube screen to show the relative positions of these deflector plates in order to facilitate explanation of this invention.

The screen of the cathode ray tube is exhibited 70 on the front of the panel 66 as shown in Figure 8 to facilitate the use of the equipment. Various modifications in the apparatus of my invention may be made, as will be apparent to those skilled in the art to which it relates. For example, dif- 75

ferent forms of electromechanically vibratile vi-
brator elements may be employed instead of the
tuning fork controlled oscillator. It is therefore
to be understood that I do not desire to limit
5 this invention to the exact details set forth except
insofar as those details may be defined by the
claims.

What I claim and desire to secure by Letters
Patent is as follows:

- 10 1. In apparatus for tuning musical instruments
the combination of a standard frequency oscillation
generator having an electromagnetic device
and a plurality of tuning forks of different pre-
determined standard frequencies, movable sup-
15 porting means for said tuning forks for moving
selected ones of said forks into predetermined
relationship with the magnetic circuit of said
electromagnetic device and means for setting the
selected fork into vibration as said fork is moved
20 into said predetermined relationship, a pick-up
device for producing pulsating electric currents
of certain sound frequencies of a musical instru-
ment the frequency characteristics of which are
25 to be determined, a cathode ray tube having a
screen, means for generating a beam of cathode
rays and a plurality of electrodes for controlling
said beam, means for impressing any one of a
plurality of said standard frequencies on selected
30 electrodes of said cathode ray tube for sweeping
said beam across said screen and means for am-
plifying and impressing electric currents corre-
sponding to said pulsating electric currents upon
other electrodes of said cathode ray tube for de-
35 deflecting said cathode ray beam in accordance with
said sound frequencies as said beam is swept
across said screen whereby the frequency char-
acteristics and sound quality of said instrument
may be observed.
2. In apparatus for tuning musical instruments
40 the combination of a standard frequency oscillation
generator having an electromagnetic device
and a plurality of tuning forks of different pre-
determined standard frequencies, movable support-
ing means for said tuning forks for moving se-
45 lected ones of said forks into predetermined re-
lationship with the magnetic circuit of said elec-
tromagnetic device and means for setting the
selected fork into vibration as said fork is moved
into said predetermined relationship to generate
50 electrical oscillations having a frequency corre-
sponding to that of the selected fork, a cathode
ray tube having a screen, means for generating
a beam of cathode rays and a plurality of elec-
trodes for controlling said beam, means for im-
55 pressing any one of a plurality of said standard
frequencies on selected electrodes of said cathode
ray tube for sweeping said beam across said
screen, a sound pick-up device for receiving
60 sounds of the musical instrument being observed
and means for amplifying and impressing elec-
trical oscillations corresponding in frequency to
said sounds upon other electrodes of said cath-
ode ray tube for deflecting said cathode ray beam
65 in accordance with said sound frequencies as said
beam is swept across said screen whereby the fre-
quency characteristics and sound quality of said
instrument may be observed.
3. In apparatus for tuning musical instruments
70 the combination of a standard frequency oscillation
generator having an electromagnetic device
and a plurality of tuning forks of different pre-
determined frequency characteristics, movable
supporting means for said tuning forks for mov-
75 ing selected ones of said forks into predeter-
mined relationship with the magnetic circuit of
- said electromagnetic device and means for set-
ting the selected fork into vibration as said fork
is moved into said predetermined relationship,
a cathode ray tube having a screen, means for
generating a beam of cathode rays and a plurality
5 of electrodes for controlling said beam, means for
producing electrical oscillations of saw-tooth
wave form corresponding in frequency to any one
of a plurality of said standard frequencies and
means for impressing said saw tooth oscillations
10 on selected electrodes of said cathode ray tube for
sweeping said beam across said screen, a sound
pick-up device for receiving sounds of the musical
instrument being observed and means for ampli-
fying and impressing electrical oscillations cor-
15 responding in frequency to said sounds upon other
electrodes of said cathode ray tube for deflecting
said cathode ray beam in accordance with said
sound frequencies as said beam is swept across
said screen whereby the frequency characteristics
20 and sound quality of said instrument may be
observed.
4. In apparatus for tuning musical instruments
the combination of a standard frequency oscillation
generator having an electromagnetic device
and a plurality of tuning forks of different pre-
determined frequency characteristics, movable
supporting means for said tuning forks for mov-
ing selected ones of said forks into predetermined
relationship with the magnetic circuit of said elec-
tromagnetic device and means for setting the
selected fork into vibration as said fork is moved
into said predetermined relationship, a pick-up
device for producing pulsating electric currents
of certain sound frequencies the frequency char-
acteristics of which are to be determined, an in-
dicating device for producing a visible pattern re-
sulting from the combined effects of the selected
standard frequency and the sound frequency be-
ing measured.
5. In apparatus for tuning musical instruments
the combination of a standard frequency oscillation
generator having an electromagnetic device
and a plurality of tuning forks of different pre-
determined frequency characteristics, a rotatable
45 disc-like supporting means for said tuning forks,
said supporting means having holes formed
around the circumference thereof for receiving
the bases of said tuning forks, means for rotating
said supporting means for moving selected ones
50 of said forks into predetermined relationship with
the magnetic circuit of said electromagnetic de-
vice and means for setting the selected fork into
vibration as said fork is moved into said pre-
determined relationship, a pick-up device for pro-
55 ducing pulsating electric currents of certain
sound frequencies the frequency characteristics
of which are to be determined, an indicating de-
vice for producing a visible pattern resulting from
the combined effects of the selected standard fre-
60 quency and the sound frequency being measured.
6. In apparatus for observing characteristics of
sounds of musical instruments and the like, the
combination of an oscillation generator including
a plurality of electromechanically vibratile vi-
brators of standard predetermined frequencies
65 corresponding to the frequencies of an octave of
a musical scale, movable supporting means for
said vibrators for moving selected ones of said
vibrators into operative position in said gener-
70 ator and means for setting the selected vibrator
into vibration as it is selected, a cathode ray tube
having a screen, means for generating a beam of
cathode rays and a plurality of electrodes for
controlling said beam, means for impressing any
- 75

one of a plurality of said standard frequencies on selected electrodes of said cathode ray tube for sweeping said beam across said screen, a sound pick-up device for receiving sounds of the musical instrument being observed and means for amplifying and impressing electrical oscillations corresponding in frequency to said sounds upon other electrodes of said cathode ray tube for deflecting said cathode ray beam in accordance with said 10 sound frequencies as said beam is swept across said screen whereby the frequency characteristics and sound quality of said instrument may be observed.

7. In apparatus for tuning musical instruments the combination of a standard frequency oscillation generator having a plurality of standard frequency vibrators of different predetermined frequencies, means for selecting different ones of said vibrators and setting the selected vibrator 15 into vibration for causing said oscillation generator to generate electrical oscillations having a frequency corresponding to that of the selected vibrator, a cathode ray tube having a screen, means for generating a beam of cathode rays 20 and a plurality of electrodes for controlling said beam, means for impressing any one of a plurality of said standard frequencies on selected electrodes of said cathode ray tube for sweeping said beam across said screen, a sound pick-up device for 25 receiving sounds of the musical instrument being observed and means for amplifying and impressing electrical oscillations corresponding in frequency to said sounds upon other electrodes of said cathode ray tube for modulating said cathode 30 beam in accordance with said sound frequencies as said beam is swept across said screen whereby the sound quality of and wave form of the sounds received from said instrument may be observed on said screen.

40 8. In apparatus for tuning musical instruments the combination of a standard frequency oscillation generator having an electromagnetic device and a plurality of tuning forks of different predetermined frequency characteristics, said electromagnetic device having a magnetic circuit adapted to include selected ones of said tuning forks, means for setting the selected fork into vibration when said fork is included in the magnetic circuit of said electromagnetic device, a 45 cathode ray tube having a screen, means for generating a beam of cathode rays and a plurality of electrodes for controlling said beam, means for producing electrical oscillations of saw-tooth wave form corresponding in frequency to any one 50 of a plurality of said standard frequencies and means for impressing said saw tooth oscillations on selected electrodes of said cathode ray tube for sweeping said beam across said screen, a sound pick-up device for receiving sounds of the musical 55 instrument being observed and means for amplifying and impressing electrical oscillations corresponding in frequency to said sounds upon other electrodes of said cathode ray tube for modulating said cathode ray beam in accordance with said sound frequencies as said beam is swept across said screen whereby the sound quality of and wave form of the sounds received from said instrument may be observed on said screen.

60 9. In apparatus for observing characteristics of sounds of musical instruments and the like, the combination of an oscillation generator including means for producing a plurality of standard predetermined frequencies corresponding to the frequencies of selected musical tones, a cathode ray tube having a screen, means for gener-

ating a beam of cathode rays and a plurality of electrodes for controlling said beam, means for impressing any one of said plurality of standard frequencies corresponding to said musical tones on selected electrodes of said cathode ray tube 5 for sweeping said beam across said screen at a rate determined by the selected musical tone, a sound pick-up device for receiving sounds corresponding substantially to the aforesaid musical tone selected or to harmonics thereof, of the 10 musical instrument being observed and means for impressing electrical oscillations corresponding in frequency to said sounds upon other electrodes of said cathode ray tube for modulating said cathode ray beam in accordance with said 15 sound frequencies as said beam is swept across said screen whereby the sound quality of and the wave form of the sounds received from said instrument may be observed on said screen.

10. In apparatus for observing characteristics of sounds of musical instruments and the like, the combination of an oscillation generator including means for producing a plurality of standard predetermined frequencies corresponding to the frequencies of an octave of a musical scale, 20 a cathode ray tube having a screen, means for generating a beam of cathode rays and a plurality of electrodes for controlling said beam, means for impressing any one of said standard frequencies on selected electrodes of said cathode ray tube for sweeping said beam across said screen at a rate determined by the selected standard frequency, a pick-up device for producing electrical oscillations corresponding to sound 25 frequencies of the musical instrument being observed and means for impressing said electrical oscillations upon other electrodes of said cathode ray tube for deflecting said cathode ray beam substantially at right angles to the direction of the aforesaid sweeping, in accordance with said 30 sound frequencies as said beam is swept across said screen whereby the frequency characteristics and sound quality of said instrument may be observed on said screen.

40 11. In apparatus for observing characteristics of sounds of musical instruments and the like, the combination of an oscillation generator including a plurality of vibrators of standard predetermined frequencies having a predetermined relation to each other in a musical scale, means for 45 selecting one of said vibrators and means for generating electrical oscillations in accordance with the vibrations thereof, a cathode ray tube having a screen, means for generating a beam of cathode rays and a plurality of electrodes for controlling said beam, means for impressing any one of a plurality of said standard frequencies on selected electrodes of said cathode ray tube for sweeping said beam across said screen periodically 50 in accordance with the selected frequency in the musical scale, a pick-up device for producing electrical oscillations corresponding in wave-form substantially to selected tones of the musical instrument being observed and means for impressing said electrical oscillations upon other electrodes of said cathode ray tube for deflecting said cathode ray beam in a direction substantially at right angles to said sweeping direction, in accordance with said tonal frequencies as said beam is swept across said screen whereby the frequency characteristics and sound quality of said instrument may be observed on said screen.

55 12. In apparatus for observing characteristics of sounds of musical instruments and the like, the combination of an oscillation generator in-
